UNITED STATES PATENT OFFICE

CARLOS J. MCKINNEY, OF DETROIT, MICHIGAN

WINDOW GUIDE CHANNEL

Application filed March 15, 1930, Serial No. 435,987. Renewed February 29, 1932.

This invention relates to window guide channels and more particularly of the type as used in automobile bodies where the edge of the glass pane is guided in suitable channels.

An object of the present invention is to provide a channel guide of this character that is inexpensive in construction and will grip the edges of the glass panel with sufficient spring tension to keep the same from rattling while still permitting vertical movement to be imparted thereto.

Another object of the present invention is to provide a guide channel consisting of a resilient, one-piece sheet metal body portion having throughout its entire length integral tongues extending therefrom either generally parallel or at an angle toward each other and suitable glass-engaging cushioning means, such as a rubber strip on one face of the sheet metal portion having the edges thereof bent around the ends of the tongues of the metal body portion, the two faces of the rubber strip adhering together where they come in contact between the tongues, and a fabric strip cemented to the rubber strip for engaging the sides and the vertical edges of the glass pane.

Another object of the invention is to provide a device of this character in which the sides of the channel not only have sufficient resiliency to engage glass panes of varying thicknesses to prevent the same from rattling, but also, have sufficient flexibility or yieldability to permit of twisting or bending of the channel, whereby said channel is enabled to meet rather extreme demands, such as use, for example, in a window frame groove which is not in a straight line.

These objects and the several novel features of the invention are hereinafter more fully described and claimed and preferred forms of construction by which these objects are attained are shown in the accompanying drawing in which—

Fig. 1 is a sectional perspective view of one form of my improved guide channel engaging a glass pane.

Fig. 2 is a sectional view taken on line 2—2 of Fig. 1.

Fig. 3 is a detail plan view of one end of the sheet metal backing strip of the channel of Figs. 1 and 2.

Figs. 4 and 5 are detail views similar to Fig. 3 showing modified forms of backing strips.

Referring now to the drawing wherein like reference characters designate like parts throughout the several views, the sheet metal backing strip 1 of the present channel comprises a solid central portion 2 having tongues 3 extending from both edges of the central portion 2, said tongues being provided or formed by slotting or notching the sides of said strip, as will be readily understood. As will be noted from Fig. 3 the transversely disposed tongues 3 are longitudinally spaced apart for a rubber-adhering purpose to be later described, as well as for purposes of general flexibility or yieldability of the channel. It is to be understood that the metal backing strip may be constructed in a variety of different forms some of which are shown in Figs. 4 and 5. In Fig. 4 the tongues 3 are made wider at their outer or free ends than they are at their inner ends where they connect to the central portion 2. As shown in Fig. 5, the metal backing strip may be perforated as indicated at 5 and if desired the outer edges thereof may be split centrally of the apertures 5 as indicated at 6. As best illustrated in Figs. 1 and 2, the sheet metal backing strip is adapted to be bent into generally channel shape, the strip central portion 2 forming the base of the channel and the tongues 3 forming the side flanges thereof, all as will be readily understood. If desired and as shown, the tongues 3 may be bent in toward each other as indicated at 7. The outer or free ends of the tongues 3, which may constitute the outer or free edges of the channel side flanges, are spaced from each other to form a vertically extending opening 8 for receiving the sides of the sliding glass 9 therebetween. For cushioning purposes, the metal backing strip is here shown as provided with a rubber strip 10 secured to the face thereof nearest the edge of the pane 9.

The longitudinal edge portions of said rubber strip are then bent around the ends of

the tongues 3 and then back along the outer faces of the said tongues as indicated at 11.

The rubber strip 10 may be made of gum rubber or treated with a composition so that 5 when the two rubber surfaces come together through the interstices or slots between the tongues 3 they will adhere together as best illustrated in Fig. 2. In the embodiment of the invention shown in Figs. 1 and 2, a fabric 10 strip 12 of the approximate width of the rubber strip 10 is cemented to the inner face of the rubber strip, that is, the face or surface nearest the pane of glass 9. The edge of the glass pane 9 will slide against the fabric strip 15 12 at a point in line with the center line of the central portion 2 of the backing strip 1, while the fabric material that is bent around the ends of the tongues 3 will engage the sides of the pane of glass 9 near its outer edges to 20 keep the same from rattling due either to motion of the vehicle or the pressure of the wind exerted thereon. It will be understood that the metal backing strip 1 and the fabric strip 12 and the rubber strip 10 may all 25 be united together to form one strip and then said resulting strip bent into generally channel shape or the backing strip 1 may be first formed in the generally channel shape as indicated in Fig. 1, and then the fabric 30 and rubber applied to it. It will be understood also that other forms of cushioning means may be provided, the form here shown in Figs. 1 and 2 and herein described being 35 illustrative merely of one embodiment of the present invention. It will thus be seen that I have provided a guide channel of inexpensive construction and which may be quickly and easily assembled and that the guide channel 40 will allow free sliding movement of the pane of glass while still keeping the same from vibration.

It will also be seen that inasmuch as the rubber and fabric strips are compressible to a certain extent, different variations in the 45 width of the glass inserted in the guide channel will be compensated for and also the resilient metal tongues 3 being of sufficient flexibility will permit the insertion of different thicknesses of glass in the guide channel, and 50 will also permit twisting and bending of the channel, all as will be readily understood.

Having thus fully described my invention, its utility and mode of operation, what I claim and desire to secure by Letters Patent 55 of the United States is—

1. A guide channel, including a generally channel-shaped sheet metal member having a base and a pair of side flanges, said side flanges being each provided with transversely disposed tongues the outer or free ends of 60 which constitute the outer or free edges of said side flanges, a rubber strip secured to the inner surfaces of said base and side flanges and having its longitudinal edge portions 65 folded outwardly around the outer or free

ends of the tongues of both of said side flanges, and a fabric strip secured to said rubber strip and having its longitudinal edge portions overlying the longitudinal edge portions of said rubber strip.

70

2. A guide channel, including a generally channel-shaped sheet metal member having a base and a pair of side flanges, each of said side flanges being provided with transversely disposed tongues, a rubber strip secured to the inner surface of said base and to both the inner and outer surfaces of the tongues of each of said side flanges, and a fabric strip secured to and overlying said rubber strip 75 throughout its width.

75

3. A guide channel, including a generally channel-shaped sheet metal member having a base and a pair of side flanges each of said side flanges being provided with transversely disposed and longitudinally spaced tongues, the outer or free ends of said tongues constituting the outer or free edges of said side flanges, rubber cushioning means folded around the outer or free ends of the tongues of each of said side flanges, said cushioning means being of such character that the portions thereof coming together through the spaces between tongues will adhere to each other, and fabric means secured to said rubber cushioning means and adapted for glass engaging purposes.

85

4. A guide channel, including a generally channel-shaped sheet metal member having a base and a pair of side flanges, each of said side flanges being provided with transversely disposed and longitudinally spaced tongues, the outer or free ends of said tongues constituting the outer or free edges of said side flanges, rubber cushioning means folded around the outer or free ends of the tongues of each of said side flanges, said cushioning means being of such character that the portions thereof coming together through the spaces between tongues will adhere to each other, and fabric means secured to and overlying said cushioning means and adapted for glass-engaging purposes.

90

5. A guide channel, including a generally channel-shaped sheet metal member having a base and a pair of side flanges, each of said side flanges being provided with transversely disposed and longitudinally spaced tongues, cushioning means secured to the inner surface of said base and to both the inner and outer surfaces of the tongues of each of said side flanges, and fabric means secured to said cushioning means and adapted for engagement with the edge and the marginal side portions of a glass pane inserted into said channel-shaped member.

105

6. A guide channel, including a one-piece generally channel-shaped sheet metal member having a base and a pair of side flanges, each of said side flanges being provided with transversely disposed and longitudinally 110

110

spaced slots, each of said slots being relatively narrow and having a length almost as great as the width of a side flange, and glass-engaging cushioning material for at least parts of the inner surfaces of said side flanges.

7. A guide channel, including a one-piece generally channel-shaped resilient sheet metal member having a base and a pair of side flanges, each of said side flanges being provided throughout substantially its entire length with transversely disposed and relatively closely spaced slots, each of said slots being relatively narrow and having a length almost as great as the width of a side flange, and glass-engaging cushioning material for at least parts of the inner surfaces of said side flanges.

8. A guide channel, including a one-piece generally channel-shaped resilient sheet metal member having a base and a pair of side flanges, each of said side flanges being provided with transversely disposed slots extending to the outer or free edge thereof, said slots being longitudinally spaced to provide alternating, correspondingly disposed tongues, and glass-engaging cushioning material for at least parts of the inner surfaces of said side flanges.

9. A guide channel, including a one-piece generally channel-shaped resilient sheet metal member having a base and a pair of side flanges, each of said side flanges being provided with transversely disposed slots each extending from substantially the inner end of a side flange to the outer or free edge thereof, said slots being longitudinally spaced to provide alternating, correspondingly disposed, yieldable tongues, and glass-engaging cushioning material for at least parts of the inner surfaces of said side flanges.

10. A guide channel, including a one-piece generally channel-shaped resilient sheet metal member having a base and a pair of side flanges, each of said side flanges having a series of transversely disposed and longitudinally spaced tongues, the outer end of each of said tongues having a width greater than that of the inner end thereof, and glass-engaging cushioning material for at least parts of the inner surfaces of said side flanges.

11. A guide channel, including a one-piece generally channel-shaped resilient sheet metal member having a base and a pair of side flanges, each of said side flanges having a series of transversely disposed and longitudinally spaced tongues, each of said tongues being of increasing width from the inner end thereof to the outer end thereof, and glass-engaging cushioning material for at least parts of the inner surfaces of said side flanges.

In testimony whereof I sign this specification.

CARLOS J. McKINNEY.
